UNITED STATES PATENT OFFICE.

WILLIAM R. WILLIAMS, OF LAWRENCE, KANSAS.

ADJUSTABLE CHART.

SPECIFICATION forming part of Letters Patent No. 660,175, dated October 23, 1900.

Application filed March 15, 1900. Serial No. 8,747. (No model.)

To all whom it may concern:

Be it known that I, WILLIAM R. WILLIAMS, a citizen of the United States, and a resident of Lawrence, in the county of Douglas and 5 State of Kansas, have invented certain new and useful Improvements in Skirt-Cutting Charts, of which the following is a specification.

My invention relates to improvements in 10 adjustable skirt-charts, and aims to provide a device by the use of which ladies' skirts of any preferred style may be cut direct from the material with perfect accuracy without the employment of any special patterns and 15 with the number of measurements of the form of the wearer and the amount of fitting required reduced to a minimum, thus resulting in great economy of time and labor and enabling any person of ordinary skill, without 20 special education or experience in the art, to cut a skirt of any style conforming to all necessary requirements.

My invention relates especially to a skirt-chart having the general contour of one of 25 the sections or gores of a skirt, said chart being provided with scales of inches around all its edges, a series of intermediate scales extending longitudinally of the chart and indicated by perforations through the body of 30 the chart, and a plurality of pivoted extensions or slides located at the corners of the chart, said slides being also provided with scales indicated thereon to be used in connection with the scales of the chart proper.

35 In the accompanying drawings, Figure 1 is a top plan view of one of my skirt-charts with the pivoted slides attached thereto extended in position for use, the position of such slides when not in use being shown by 40 dotted lines. Fig. 2 is an enlarged detached view of the extension or slide employed in cutting circular skirts or other skirts having wide gores. Figs. 3, 4, 5, and 6 are enlarged detached views of four other pivoted slides 45 employed in connection with my device.

The chart may be made of any suitable material having the requisite tenacity and durability, preferably of heavy document Manila cardboard having a smooth-surface finish, 50 and the various lines, inscriptions, &c., upon the chart are printed thereon, preferably from a lithographic plate.

The chart is made of the full size as to both length and width and of the general shape of one of the sections or gores of an ordinary skirt when of single thickness, the intention being to make the chart long enough and wide enough for cutting any skirt likely to be called for, provision being made, as herein described, for any degree of reduction from the maximum size.

The chart is always properly used with the lower edge 1, as shown in Fig. 1, toward the operator, and this edge may therefore be termed the "front" edge, the edge 2, corresponding to the waist-line, being at the left end of the chart, and the edge 3, corresponding to the bottom of the skirt, being at the right end. The slides 4 5 6 7 8, the use of which will be hereinafter explained, are rotatably attached to the under surface of the chart by pivots 9 10 11 12 13, respectively, and, with the exception of No. 8, are supported on the chart, at the ends opposite their pivots, by pin-and-slot joints 14 15 16 17, respectively, headed pins attached to the slides extending through curved slots in the chart. The slides may be moved in and out by pressure applied to the heads of said pins, which are larger than said slots.

In the case of the slide 8 for cutting circular skirts a tuck or loop is provided, as shown in dotted lines in Fig. 1, on the under side of the chart, within which the end of the slide is inserted when not in use. Said slide is also 85 provided with a button or stop 18, which is made to abut against the upper edge of the chart when in use to hold the slide 8 in working position at the proper point.

The front edge 1 of the chart is provided 90 with a scale of inches, measured from the waist-line 2 and extending therefrom preferably to a distance of forty-three and one-half inches, all above and including eighteen inches being indicated in figures inscribed on 95 the scale. The waist-line 2 is preferably six inches in length, not including either of the slides 4 8. Said line is an arbitrary curve which has been found in practice to be the proper one to secure the best fit of the skirt 100 and also the best hanging effect. Six inches to the right from said waist-line 2 a hip-line 19 is indicated on the chart in dotted or full lines, as preferred, said hip-line 19 being

parallel with waist-line 2. Beginning at a point where said hip-line 19 intersects the front edge of the chart, said front edge extends in a straight line to the right-hand edge 5 of the chart, and the upper or rear edge of the chart is also a straight line from the point where said hip-line intersects said rear edge to the right-hand edge of the chart. Between said hip-line and waist-line the curves of the 10 front and back edges are arbitrary, being such as have been found to secure the best results. Said right-hand edge is formed on an arbitrary curve, which has been found in practice to be the proper one to make the 15 skirt hang parallel with the floor, and said edge is provided with a scale graduated from one to twenty-two inches, extending from front to back.

About centrally of the chart a line (designated as scale I) extends from the left-hand edge to the right-hand edge, meeting the latter at the eleven-inch mark and meeting the hip-line about half-way between the front and back edges, after which said line is continued to the waist-line parallel with the back edge. Along the right-hand end of said line is arranged a series of perforations 21 through the chart, said perforations being one-half inch apart, beginning with the minimum length of a lady's skirt—say twenty-nine inches—and extending to forty-four inches at the right-hand edge.

Before proceeding further with the description of the chart an illustration will be given 35 of its use in cutting one of the gores of an ordinary skirt—for example, the front gore. The material being first spread out upon a table, and of double thickness in this case, the chart is laid upon the goods with its front 40 edge coinciding throughout with the fold of the goods and with slide 4 extended. A mark is then made on the goods to indicate the width of the gore at the top or waist-line, such point being found on the scale or line 2 45 at a proper distance from the corner of slide 4, extended usually three inches for a slender or medium figure. A mark is then made on the goods at the front edge of the chart to indicate the length of front—say, for example, 50 forty inches. A mark is then made through one of the perforations in scale I to indicate the length of the back edge of the gore, which should be one-half inch longer than the front edge to give proper curvature to the bottom 55 edge. The chart is then moved on the goods or drawn toward the operator and placed so that its back edge will coincide with the marks made at the waist-line and in scale I. A line is then drawn on the goods between 60 the points mentioned, using the back edge of the chart as a ruler or guide, after which a cut through the goods is made near said line, proper allowance being made for seam. The chart is then moved to the left until its right-hand edge coincides with the points previously fixed to indicate the length of skirt, which edge is then used as a guide for draft-

ing the bottom curve in a similar manner. An ordinary skirt being composed of a front and back gore and two or more side gores, 70 the next step is to cut the side gores. For this purpose an additional scale E is provided on the chart, extending from end to end thereof about four inches from the back edge and eighteen inches from the front edge 75 at the bottom line 3. The gradations of said scale are indicated by a row of perforations extending through the chart one-half an inch apart and numbered toward the right from twenty-nine to forty-four and one-half 80 inches. The lower edge of the chart is placed on the straight edge of the goods, the proper measurement of the waist-line of the gore indicated on the goods at the proper point on scale 2, and the length of the front edge 85 of the side gore marked at the proper point on scale 1, which, to continue the previous illustration, would be forty and one-half inches. The back edge of the side gore is then located at the proper point on scale E 90 by marking through the perforation at that point or at forty-one inches. The chart is then moved toward the operator and a line drawn on the goods, as before, between the points marked, from which line the proper 95 cut may be made. The lower line of the gore is then located by using the right-hand edge of the chart, as before described. The second side gore usually employed would be drafted in the same manner. The back gore, 100 if made with a central seam, as usual, would be drafted in the same manner as the front and side gores, except that for this purpose, the back gore being the widest section of the skirt, the entire width of the chart is usually 105 employed, its front edge being used to locate and draft the front edge of said gore and its back edge for the back edge of said gore.

The description of the construction and uses of the chart thus far has referred to the 110 drafting of ordinary skirts. For drafting flaring or bell-shaped skirts additional curved scales J and K are provided, lying near the straight scales I and E, respectively, but curving forward from said scales from near 115 the hip-line downward for about two-thirds of the length of the skirt. Said curved scales J and K are indicated by perforations about two inches apart, through which, in practice, marks are made on the material, and after 120 the chart is removed the proper line is located by tracing for back edge of front or side gore from point to point thus indicated. The continuation of this curved line to the bottom of the skirt is made by the use of the 125 slide 6. The back edge of the chart is brought to coincide with the ends of the curved line before located, and slide 6 is then extended as far as necessary, according to the degree of flare desired, and the draft then completed 130 by using the rear edge of said slide as a guide. The end of the gore is drafted in the manner before described for the ordinary gores, except that the end of the slide is utilized for the part

included in the flare. A curved scale L (indicated by perforations) is also provided, extending along the front edge of the chart, for drafting the front line of the side and back 5 gores of flaring skirts. In practice the front edge of the chart is made to coincide with the front edge of the material and the perforations utilized in locating the upper portion of the line of the gore in the manner before 10 described for the back edges. The slide 5 is utilized for drafting the bottom extension of the front and lower edges of said gore for flaring skirts in the same manner as slide 6 is used, as before described.

15 The slide 4 is used extended, as in Fig. 1, for drafting the front gore in order to secure the proper front line for said gore, but is not used for the side gores, the front lines of which conform at this point to the shape of 20 the chart proper.

The slide 7 is for straightening and raising the waist-line when cutting the back gore on the fold of the goods or without a seam in the center of said gore. If said gore is made 25 with a central seam, the waist-line is conformed to the shape of the chart proper.

For drafting and cutting circular skirts or other skirts or gores with wide tops an additional scale F is provided on the chart and 30 the elongated graduated extension 8, pivoted on the chart at 13. Said scale F is located in the upper right-hand corner of the chart, parallel with its upper edge and about two 35 inches therefrom. It is indicated by perforations about one-half inch apart placed opposite the figures of the scale on the upper edge of the chart, so that said figures may be utilized in connection with scale F.

The extension 8 is provided with a scale of 40 inches measuring when in operative position from the lower left-hand corner of the chart, with the slide 4 extended a distance, preferably, of twenty-two and one-half inches. The left-hand edge of said slide is a continuation 45 of the curve of the waist-line 2 of the chart proper and is an arbitrary curve found in practice to be correct. The figures on the scale represent measurements on the waist-line from front to back. At the right of said 50 figures are lines and inscriptions indicating the total net waist measurements to which the figures on the scale correspond, the figures on the scale indicating the width of the top of one side of the skirt, (both sides being 55 usually cut at once,) and therefore the distance to be marked off on the goods for the top line of the skirt in drafting it. From this top line is to be deducted the "darts" or arrow-shaped excisions to be made in order to 60 get the proper fit at the waist. For example, if the waist-line of the skirt when completed is to have a total measurement of twenty-four inches the mark on the goods (the same being doubled or "faced") is to be 65 made at the eighteen-inch point on the scale, which represents thirty-six inches, including both thicknesses of the material. The ex-

cisions for darts, fullness, &c., usually taking up six inches on each side, or twelve inches altogether, will reduce the thirty-six 70 inches to twenty-four inches, the net measurement desired. The waist-line for the circular skirt having been located and marked on the goods, as described, using the edge of extension 8 as a guide, the front edge of the chart 75 is applied to the fold of the goods and the length of front marked off in the same manner as for the front gores of ordinary skirts. A mark is then made on the goods through the proper perforation in scale F, dropping 80 one inch lower than the point located on the front line. A mark is also made on the goods at the hip-line on the upper edge of the chart. The chart is then moved forward until its front edge coincides with the point thus located and the same process repeated, the waist-line of the chart proper being always 85 made to coincide with the curved line previously drawn on the goods by the use of extension 8 and the lower line of the skirt being drafted by using the right-hand edge of the chart in the manner before described for gores of ordinary skirts. After this process has been performed three times the back 90 edge of the skirt is drafted by using the back edge of the chart as a guide, as in the case of the gores. In this process the waist-line is not to be allowed to overrun the measurement previously made for such line, and, if necessary, any excess would be taken off by 95 placing the upper left-hand corner of the chart at the limit of waist measurement (eighteen inches in the example given) and drafting the back edge with the chart in that 100 position.

At the edge 2 or waist-line of the chart, as at 22, and also on extension 8, are indicated converging lines to be used as a guide in drafting the darts or excisions to be made to take out fullness at the waist-line. A series 105 of perforations 23 in the body of the chart provides for locating the point of the dart, and the side lines may be located by marking on the goods at the outer margins of the darts. In the case of the dart indicated on 110 extension 8 no perforations are necessary as the width of the extension corresponds to the 115 proper length of the dart.

Figs. 3, 4, 5, and 6 are enlarged details of 120 slides 4 5 6 7. Slides 5 and 6 are provided on their curved ends with scales to aid in fixing the amount of curvature in the gores of flaring skirts. Slides 4 and 7 are not provided with scales, but simply with inscriptions indicating their uses.

The foregoing illustrations and description have been given to indicate the general method of using the chart and its various features and accessories, details unnecessary in a specification being omitted. The various scales on the chart are accompanied by 130 inscriptions for the benefit of operators, indicating the uses of said scales.

The only actual personal measurements re-

quired preliminary to the use of the chart are three in number—viz., the size of the waist and the length of front and back skirt. These being settled all necessary details 5 may be worked out and drafted expeditiously and correctly by the use of the chart, as described.

It is obvious that the chart may be utilized for drafting either skirts, linings, or patterns. 10 Having described my invention, I claim as new and desire to secure by Letters Patent—

A skirt-cutting chart having the shape of one of the gores of a skirt, the bottom edge thereof having the correct curvature for

drafting the bottom of the gore, the pivoted 15 extensions 5 and 6 for drafting flaring skirts; the pivoted extension 8 having one edge thereof, when extended, a continuation of the curve of the waist-line, the pivoted extension 4 for drafting front gores, and the scales 20 E, F, I, J, K, and L, all substantially as shown and described.

In testimony whereof I affix my signature in the presence of two witnesses.

WILLIAM R. WILLIAMS.
